PNEUMATIC FLY FOR STACKERS

Wilhelmus Adrianus van Berkel, Clarens, Switzerland, assignor to U. S. Slicing Machine Company, La Porte, Ind., a corporation of Indiana

Application November 14, 1931, Serial No. 575,015
In Great Britain November 28, 1930.

17 Claims. (Cl. 146—94)

This invention relates to slicing machines and particularly to slicing machines in which the slices, after they are severed by the knife, are conveyed by a special conveyor and stacking mechanism into a discharge position, at which position the slices are discharged upon a slice receiving surface. Heretofore it has been customary to discharge the slices by moving fingers arranged behind the slice when the slice is at the discharge position. Necessarily such an arrangement requires special mechanism for operating the fingers, which mechanism is subject to wear, and furthermore, the slices tend to adhere to the slice-engaging fingers so that the slices do not fall properly upon each other or upon the slice receiving surface to form a uniform stack of slices on the slice receiver.

One object of this invention, therefore, is to provide means whereby these difficulties are done away with and in carrying out this object I provide pneumatic means operated either by the slicing machine or by a separate means independent from the slicing machine for discharging air against the slice to throw the slice onto the slice receiver.

A more particular object of my invention is to provide a series of fingers or their equivalent arranged between the prongs on a conveyor and adapted to lie behind the slice at the discharge position and provide these fingers with openings through which air is discharged to throw the slice on the slice receiving surface.

A still further object of this invention resides in providing a conveying mechanism in which the slice, while in a vertical position, is fed to a slice discharge position, and hollow fingers, also arranged vertically, one above the other, having openings in the sides thereof adjacent the slice, so that air may be introduced into the fingers and discharged through the openings to throw the slice onto the slice receiving surface. With this construction I prefer to provide the fingers with openings of progressively increasing cross sectional areas from the lowermost finger to the uppermost finger so that more air will be discharged against the upper end of the slice than against the lower end, and as a result, the slice will be turned through a substantial angle into a substantially horizontal position on the slice receiver.

A still further object resides in the provision of a discharge fly which can be used as the ordinary fly is used, or, if desired, may be used as a stationary element using the air to discharge the slice. With this arrangement, if for any reason

the pneumatic discharge becomes inoperative, the mechanical discharge of the slice may still be used.

Other objects of this invention will appear hereinafter as the description thereof proceeds, the novel features, arrangements and combinations being clearly set forth in the description and in the appended claims.

In the drawings:

Fig. 1 represents a plan view of a device embodying my invention;

Fig. 2 is a side elevation thereof, viewed from the side at which the stacking mechanism is arranged;

Fig. 3 is a view looking from the side opposite from that viewed in Fig. 2, illustrating the manner in which the reciprocating table actuates the means for compressing the air used for the discharge fly;

Fig. 4 is a vertical cross section through the discharge fly;

Fig. 5 is a section taken along the line 5—5 of Fig. 4;

Fig. 6 is a horizontal section taken substantially through the pivot for the discharge fly, and

Fig. 7 shows a modified arrangement for a part of the mechanism illustrated in Fig. 2.

In Fig. 1, the reference numeral 1 indicates a reciprocating table slidably guided by the guides 2 mounted on the base 3. A crank 4 carried by a stub shaft 5 is connected by means of a pitman 6 to the under side of the table 1. When the crank 4 rotates, the result is that the table reciprocates along its guides. A flywheel 7 secured to a shaft 8 has a bevel gear 9 meshing with a bevel gear 10 secured to the stub shaft 5, so that when the flywheel is rotated the crank 4 will rotate and the table will reciprocate upon its guides.

An additional shaft 11 having a bevel gear 12 secured thereto meshing with the gear 10 is adapted to drive the knife 16, which knife is mounted on the spindle 13 rotatably mounted in the bracket 14 secured to the base 3. A chain 15 is trained over the sprockets on the shafts 13 and 11 so that a rotary motion is imparted to the knife 16. This construction is quite well known in the art to which it pertains.

Mounted on one side of the slicing machine base is a bracket 17 carrying a deflector 18 having a series of horizontally extending recesses 105 therein for the reception of the prongs 20 carried by a drum 21 rotatable with a shaft 22. As the shaft 22 rotates, the prongs 20 are carried past the edge of the knife and partly into the recesses 19 in the deflector 18. The shaft 22 is driven from

the shaft 8 by means of the bevel gears 23, 24, shaft 25 and bevel gears 26 and 27. Bevel gears 23, 24, 26 and 27 are secured respectively to the shafts 8, 25, 25 and 22. The drum 21 rotates 5 once for each complete reciprocation of the table 1.

An auxiliary bracket 28 secured to the bracket 17 has a slice receiving tray 29 thereon and this tray is adapted to receive the slices as they are 10 discharged from the drum 21. The parts are so arranged that as the slice is formed the same is engaged by the prongs 20 and due to the fact that the prongs extend partially into the recesses 19 when passing the deflector 18, the slices are 15 impaled on the prongs and held thereon until the slice reaches the discharge position. When the slice reaches the discharge position, means are provided for discharging the slice from the prongs, and this comprises, in the ordinary construction, 20 a plurality of fingers arranged between rows of prongs, the same as shown in the drawings, and a means for moving these fingers about a pivot to throw the slices on to the tray 29. In the present instance, a similar arrangement is used, 25 except that I have added pneumatic means, which is ordinarily operable to discharge the slices without relying on the fingers themselves except as means for conveying the air. The discharge fly, as is best illustrated in Figs. 4, 5 and 6, comprises 30 a hollow pivot 30 rotatably mounted in a bearing 31 on the bracket 17. An upwardly extending hollow member 32 has free communication with the interior of the hollow pivot 30 and carries a plurality of hollow fingers 33, which also communicate at 34 with the interior of the upwardly extending hollow member 32. Each of the fingers is provided with a series of openings 35. These openings are of such a size as to exert the desired amount of pressure on the slice, to turn the slice 35 from a vertical position into substantially a horizontal position to thereby stack the slices uniformly on the tray. As will be seen from an inspection of Fig. 4, the openings in the lowermost finger are not as large as those in the uppermost finger and the sizes of the intermediate openings are progressively larger from the bottom to the top.

The forward faces of the fingers are provided with grooves 36 extending substantially throughout their entire length so that when the fly is being used to directly engage the slice, the contacting surface will be minimized to thereby prevent the adherence of the slice to the fly. The fly is secured to the hollow pivot 30 by means of the pin 37.

A stationary conduit 38 is connected by means of a sleeve 39 and packing glands 40 to the rotating hollow pivot 30 and is adapted to supply air under pressure to the pivot and to the fingers of the fly. A three-way valve 44 having branches 41, 42 and 43 is arranged in the conduit 38 and is adapted to selectively supply air to the hollow pivot 30, or cut off the supply of air, if desired. In Fig. 6 air can be supplied to the hollow pivot 65 30.

Ordinarily the fingers are held in an upright position and this is accomplished by means of an arm 47 secured by a pin 48 to the hollow pivot 30 and a bolt 49 which passes through the 70 arm into a tapped opening 48' in the bracket 17. Therefore when the slice arrives at a position adjacent the slice receiving tray 29 and air is introduced through the conduit 38 to the hollow fingers 33, the slice is discharged onto the tray and 75 in addition, as discharged, is turned through a

substantial angle toward a horizontal position so that the slices, as they fall, will become stacked one upon the other. The effect of the air upon the slice 50 is indicated by the arrows 51 in Fig. 4, the arrows being made of proportionate lengths to the force of the air passing through the openings 36 of the respective fingers. It is obvious that the greatest pressure is on the uppermost end of the slice, whereas the lowermost ends of the slice are not affected a great amount by the air pressure. Consequently the upper side is thrown outwardly at a more rapid rate than the lower side and soon the slice assumes a substantially horizontal position and so falls upon the slice receiving tray or previous slice which has been cut.

In order to supply the conduit 38 with air at the proper time I provide a cylinder 52 in which reciprocates a piston 53 mounted on a connecting rod 54 extending through one end of a cylinder and having an upwardly extending projection 55 arranged within a recess 56 in the underside of the table 1. As the table reciprocates, the air is compressed between the piston 53 and the end of the cylinder 52 which lies adjacent the operator's side of the machine. The opposite end of the cylinder is either entirely open or is provided with means for admitting air to the cylinder so as not to retard the movement of the piston during the time when the air is not being supplied to the conduit 38. The cylinder 52 is secured by brackets 57' to the side of the base 3.

The table, when in the position shown in Fig. 1, is almost at the end of its return stroke and soon will begin the forward stroke to present the substance to the knife so that the slices are cut therefrom. The drum 21 rotates in a counter-clockwise direction as shown in Fig. 1 and is in a position to receive the slices on the prongs 20 substantially at the time the knife begins to sever 115 the slice from the substance. The drum, after picking up the substance, conveys the same around to the position illustrated in Fig. 1, or in Fig. 2, at which position the substance is ready to be discharged from the drum. Due to the 120 fact that the projection 55 extends into the slot 56 and may travel lengthwise relative thereto, it will be obvious that the first part of the movement of the table 1 will not compress the air in the cylinder 52, and as soon as the table has been 125 moved on its working stroke a sufficient distance, the projection 55 will be engaged by the end of the slot, and as a result, the piston rod and piston will be moved, but will not compress the air in the cylinder 52. However, on the return stroke 130 of the table 1, the same action occurs, i. e., the projection 55 travels relative to the slot but the piston is not moved until the projection is engaged by the end of the slot. Therefore the movement of the table actuates the piston 53, compresses 135 the air and forces the air through the conduit 38 to the discharge fly just as the slice arrives at the slice discharge position which is shown in Figs. 1 and 2. The slice is discharged in the manner which has already been described.

Whenever it is necessary or desirable to use the discharge fly as the ordinary discharge fly, I disconnect the bolt 49 and the pivot 30 is then free to rotate, except as restrained by the means now to be described. A cam 57 secured to the 145 shaft 22 engages a roller 59 on an arm 58 and rocks the arm 58 in a counter-clockwise direction. A compression spring arranged within the telescoping casing 60 is pivoted at 61 to the arm 58 and at 62 to a lug 63 on the underside of the 150

bracket 28 and normally urges the arm 58 in a clockwise direction. The arm 58 is formed as an extension on the member 47 and therefore when the arm 58 rotates the hollow pivot 30 will also rotate. The cam is provided with an abrupt vertical portion 64 and as soon as the shaft 22 has rotated a sufficient distance into the position shown in Fig. 2, the arm 58 is ready to move off the lowermost side of the cam along the abrupt vertical portion and the spring within the casing 60 urges the roller in this direction causing the discharge fly to move outwardly and downwardly about the pivot 30, thereby discharging the slice upon the slice receiving tray 29. A brake 65 pivotally connected at 66 to a link 67 which in turn is pivoted at 68 to the arm 58 travels along the vertically arranged braking surface 69 on the downwardly extending projection 70 on the underside of the bracket 28. As the discharge fly moves under the action of the spring in a clockwise direction, the brake 65 travels upwardly along the braking surface 69 and as a result, retards the movement of the discharge fly and especially at the end of the discharge movement. In addition, a separate spring retarding means is provided to retard the movement of the discharge fly near the end of the discharge movement, and this means comprises telescoping members 71 and 72 pivoted at 73 and 74 to the bracket 17 and to the link 67 respectively and a telescoping tension spring connected respectively at its opposite ends to the telescoping members 71 and 72. With this arrangement the link 67 is normally urged in a clockwise direction about the pivot 68 and therefore increases the frictional force with which the brake 65 is held against the surface 69.

In Fig. 7 I have illustrated a supplemental friction retarding element in the form of a spring 75 secured to the upper side of the bracket 17 by means of the screws 76 and extending downwardly through the opening 77 in opposition to the braking surface 69. The lower end of the spring extends outwardly at 78 to facilitate the entry of the brake between the spring and the braking surface 69. With this arrangement the frictional retarding force between the brake and the braking surface 69 is increased and the spring itself forms an additional braking surface whereby the discharge fly is brought to rest more quickly than where just the usual braking surface is provided. Also the spring acts to cushion the end of the movement of the discharge fly.

As will be noted from an inspection of Fig. 1, the fingers on the fly are tapered so that they are narrower at their extreme outer ends and are heavier adjacent the portions which are attached to the upright connecting portion 32. The outer curvature of the fly is so arranged as to expose a greater portion of the prongs beyond said outer surface near the ends of the fingers than adjacent the portions of the fingers which are attached to 32. This results in a "peeling" action when the slice is discharged from the prongs. In other words, as the fly moves outwardly at a uniform rate, the portion of the slice which is adjacent the part 32 is first pulled off the prongs and the remaining portions of the slice toward the ends of the fingers are successively removed from their respective prongs in a sort of peeling action which prevents the slice from being torn. The result is that the slices which are deposited upon the slice receiving surface are very neat in appearance and are rendered more salable than where the slices are partially torn due to the fact that all portions

of the slice are removed from the respective prongs at the same time.

Various changes may be made in the apparatus as disclosed without departing from the spirit of this invention, and therefore I do not wish to be limited in my invention except as set forth hereinafter in the appended claims.

Having thus fully described my invention, what I claim as new and desire to obtain by Letters Patent of the United States is:

1. In a slicing machine, the combination with a knife and a table movable relative to each other, air compressing means actuated by the relative movement of said knife and table, a movable slice conveyor for conveying slices away from the knife after they are formed, a normally stationary discharge fly provided with a plurality of openings, means for actuating said conveying means to move the same in a direction to bring the slices into a position adjacent said fly and in front of said openings, communicating means between said air compression means and said openings for supplying air to said openings substantially at the time said slices arrive in front of said openings whereby to direct a plurality of streams of air against the slice to thereby turn the slice through a substantial angle onto a slice receiving surface.

2. A device as claimed in claim 1 in which the air compression means comprises a pump, means for operating said pump operatively connected to the means for reciprocating said knife and table relative to each other so that the introduction of air under pressure to said openings is synchronized with the movement of said knife and table relative to each other to insure that air is always forced through said openings in the aforesaid manner.

3. In a slicing machine, the combination with a slicing knife, means for conveying slices away from said knife as they are formed, and a movable discharge fly for removing the slices from said conveying means and for depositing same upon a slice receiving surface, means for actuating said discharge fly to move same against a slice as it arrives at discharge position, pneumatic means associated with said discharge fly for directing a series of streams of air against the side of the slice to be discharged when the slice is at the discharge position, and means for selectively rendering either of said last two mentioned means inoperative.

4. In a slicing machine, the combination with a knife, a conveyor for conveying slices away from the knife after they are formed, a discharge fly for discharging slices off said conveyor onto a slice receiving surface, mechanical means for moving said discharge fly into discharge position, means for resisting movement of said fly into discharge position comprising a brake slidably engaging a braking surface, and means for increasing the frictional resistance of said brake on said surface at the end of its movement therealong comprising an auxiliary member arranged in opposed relation to said first braking surface to engage said brake only near the end of its movement and force said brake against said first braking surface to thereby increase the frictional resistance on both the first braking surface and said auxiliary member whereby to suddenly arrest the movement of said discharge fly to insure the removal of the slice therefrom and to decrease the distance necessary to move the fly to properly discharge the slice therefrom at a predetermined place.

5. In a slicing machine, the combination with a knife, a conveyor for conveying slices away from the knife after they are formed, a discharge fly for discharging slices off said conveyor onto a slice receiving surface, mechanical means for moving said discharge fly into discharge position comprising a brake slidably engaging a braking surface, and means for increasing the frictional resistance of said brake on said surface at the 10 end of its movement therealong comprising a flat spring arranged in opposed relation to said first braking surface to engage said brake only near the end of its movement and force said brake against said first braking surface to thereby increase the frictional resistance on both the 15 first braking surface and said flat spring whereby to suddenly arrest the movement of said discharge fly to insure the removal of the slice therefrom and to decrease the distance necessary 20 to move the fly to properly discharge the slice therefrom at a predetermined place.

6. In a slicing machine, the combination with a slicing knife, a movable element having slice engaging prongs thereon for receiving a slice as 25 it is formed and for moving the slice to a discharge position, means for forcing the slice onto said prongs so that said prongs will hold the slice as said element moves the slice to a discharge position, and a discharge fly having means arranged adjacent the path of travel of said slice as it moves into discharge position for engaging the slice as it moves to discharge position, the engaging surface of said discharge fly remaining stationary until the slice is in position to be discharged, the slice engaging surface of said discharge fly being arranged slightly at an angle to the path of movement of the slice, said angle being inclined outwardly toward the ends of said prongs from the portion of said discharge fly 35 which first engages the slice to the portion thereof which subsequently engages said slice, whereby the slice is partially stripped from said prongs prior to the movement of said discharge fly into discharge position, whereby when said discharge fly is moved to an inoperative position, the slice 40 is peeled from successive prongs in the direction of movement of the slice, at successive intervals of time and not simultaneously.

7. A discharge means for slicing machines comprising a conveying element having prongs upon which the slice is impaled after it is formed, and in substantially equal amounts on all of said prongs, and a discharge fly arranged in the path of movement of said slice and adapted to pass between adjacent prongs on the side of the slice which lies adjacent the bases of said prongs, said discharge fly having a period of rest which lasts substantially until the entire slice is against said discharge fly or in a position to be engaged thereby and thereafter moving outwardly to strip the slice from said prongs, the slice engaging surface of said fly being inclined with respect to the path of movement of said slice while the discharge fly is at rest with that portion of the discharge fly which first engages the slice lying farther away from the points of said prongs than the portions which subsequently engage the slice whereby during the movement of the slice into a position to be discharged from the prongs, the 50 advance end of the slice is partially stripped from the prongs so that when the discharge fly is moved to remove the slice from the prongs, the advance portion of the slice is first stripped from the prongs followed in quick succession by 55 the other portions of the slice, thus effecting

a peeling action which prevents the prongs from tearing the slice.

8. In a slicing machine, the combination with a slicing knife, of a slice conveying element for conveying slices away from the knife as they are formed comprising a movable member having a plurality of rows of prongs upon which the slice is impaled, means for moving said member from a position adjacent said knife to a slice discharge position, a discharge element having a plurality of substantially parallel spaced hollow fingers positioned to pass between adjacent rows of prongs adjacent the side of the slice which is remote from the points of the prongs, said fingers having openings communicating with the interior of said hollow fingers and with the exterior portions of said fingers which lie adjacent the slice when the slice is in discharge position, and means for introducing air under pressure into said hollow fingers when the slice is at the discharge position whereby the slice is discharged from said prongs.

9. In a slicing machine, the combination with a slicing knife, of a slice conveying element for conveying slices away from the knife as they are formed comprising a movable member having a plurality of rows of prongs upon which the slice is impaled, means for moving said member from a position adjacent said knife to a slice discharge position, a discharge element having a plurality of substantially parallel spaced hollow fingers positioned to pass between adjacent rows of prongs adjacent the side of the slice which is remote from the points of the prongs, said fingers having openings communicating with the interior of said hollow fingers and with the exterior portions of said fingers which lie adjacent the slice when the slice is in discharge position, and means for introducing air under pressure into said hollow fingers when the slice is at the discharge position whereby the slice is discharged from said prongs, mechanical means for moving said discharge fly to bring the fingers against the slice and remove the slice from the prongs onto a slice receiving surface, and means for selectively rendering said last mentioned means and means for introducing air under pressure inoperative as desired.

10. A device as set forth in claim 8 in which said rows of prongs extend substantially horizontally with the rows of prongs spaced from each other in a vertical direction and in which said openings in said fingers near the uppermost rows of prongs are of a size to permit greater amounts of air to move against the slice than the openings in the fingers between the lowermost prongs, whereby the upper side of the slice is directed outwardly away from said prongs at a greater rate than the lower portion thereof so that the slice is turned from a substantially vertical position into a position at a substantial angle to the vertical as it is moved onto the slice receiving surface.

11. A device as set forth in claim 9 in which said rows of prongs extend substantially horizontally with the rows of prongs spaced from each other in a vertical direction and in which said openings in said fingers near the uppermost rows of prongs are of a size to permit greater amounts of air to move against the slice than the openings in the fingers between the lowermost prongs whereby the upper side of the slice is directed outwardly away from said prongs at a greater rate than the lower portion thereof so that the slice is turned from a substantially vertical position into a position at a substantial angle to the vertical as it is moved onto the slice receiving surface.

- gle to the vertical as it is moved onto the slice receiving surface.
12. A discharge fly for slicing machines adapted to be movably mounted in a position adjacent to the slice when the same is conveyed to a discharge position, comprising a hollow member having a plurality of openings for permitting the escape of air introduced into said hollow member, said openings facing in a direction toward the slice when the slice is in a discharge position, means for introducing air under pressure to said hollow member to move the slice onto a slice receiving surface, means for moving said discharge fly to bring said hollow member into physical contact with the slice to move the slice to a slice receiving position, and means for selectively rendering either of said last mentioned means operative or inoperative.
13. In a slicing machine, the combination with a slicing knife arranged with the cutting plane thereof extending substantially vertically, a rotating drum having a plurality of horizontally extending prongs thereon with the outer points of the prongs arranged substantially concentrically with respect to the axis of rotation of said drum, a discharge fly having arcuate horizontally extending fingers thereon having the slice engaging portions thereof of a curvature which is substantially concentric with the axis of rotation of said drum when the discharge fly is in its inoperative position just prior to discharging the slice from the drum, said fingers being hollow to provide air chambers therein, openings leading from said air chambers through those sides of the fingers which lie adjacent the slice as the slice arrives at discharge position, means for introducing air under pressure into said chambers when a slice is at the discharge position, whereby the slice is moved off said prongs onto a slice receiving surface.
14. In a slicing machine, the combination with a slicing knife arranged with the cutting plane thereof extending substantially vertically, a rotating drum having a plurality of horizontally extending prongs thereon with the outer points of the prongs arranged substantially concentrically with respect to the axis of rotation of said drum, a discharge fly having arcuate horizontally extending fingers thereon having the slice engaging portions thereof of a curvature which is substantially concentric with the axis of rotation of said drum when the discharge fly is in its inoperative position just prior to discharging the slice from the drum, said fingers being hollow to provide air chambers therein, openings leading from said air chambers through those sides of the fingers which lie adjacent the slice as the slice arrives at discharge position, means for introducing air under pressure into said chambers when a slice is at the discharge position, whereby the slice is moved off said prongs onto a slice receiving surface, said discharge fly being also movably mounted to physically engage the slice when it is at the discharge position, means for moving the discharge fly against the slice to move the slice onto a slice receiving surface, and means for rendering said last mentioned means and the means for introducing air under pressure inoperative selectively as desired.
15. A discharge fly for slicing machines comprising a plurality of hollow fingers, a support for said hollow fingers having a duct communicating with the interiors of said hollow fingers, a bearing member for said support, a hollow tube extending through said bearing member, means for securing said support to said hollow tube so as to rotate therewith, said hollow tube having a communication with said duct, means for introducing air under pressure to said hollow tube whereby the air is conveyed to the interiors of said hollow fingers, said hollow fingers having openings communicating with the interiors thereof and with external faces of said fingers which lie adjacent the slice at a discharge position, and means selectively operable for moving said discharge fly about its pivot.
16. In a slicing machine the combination with a slicing knife of means for presenting a substance to be sliced to said knife, movable means for receiving and conveying slices away from said knife after they are formed, means for actuating said conveying means to move the slices to discharge position, a member located at said discharge position having a plurality of spaced openings therein through which air may be discharged against the side of the slices as they arrive at discharge position and means for supplying air under pressure to said openings, said openings varying in their dimensions to spread and turn the slices through a substantial angle on to a slice receiving surface after said slices have been conveyed to said discharge position in front of said openings by said conveying means and means for selectively moving said member to bring the same into physical engagement with said slices to discharge the slices from said conveying means as desired, whereby either the air alone, the member alone, or the latter two elements in conjunction with each other may be used to discharge the slices from said conveying means.
17. In a slicing machine, the combination with a slicing knife, of a conveying element for conveying slices away from the knife as they are formed and for moving them to a discharge position, a discharge fly movably mounted adjacent the discharge position, means for actuating said discharge fly to move the slices off said element when the slices arrive at the discharge position by physical contact therewith, said fly being provided with means whereby air may be directed under pressure against the side of the slice adjacent the fly to move the slice off said conveying element, and means for selectively rendering the discharge fly inoperative to force the slices off said element by physical contact therewith whereby the air under pressure which is directed against the slice forces the slice off said element.

WILHELMUS ADRIANUS VAN BERKEL.
